UNITED STATES PATENT OFFICE.

EDWARD DAWSON, OF TERRE HAUTE, INDIANA, ASSIGNOR OF ONE-HALF
TO PETER N. STAFF, OF SAME PLACE.

VICE.

SPECIFICATION forming part of Letters Patent No. 412,166, dated October 1, 1889.

Application filed April 2, 1889. Serial No. 305,708. (No model.)

To all whom it may concern:

Be it known that I, EDWARD DAWSON, a citizen of the United States, residing at Terre Haute, in the county of Vigo and State of Indiana, have invented certain new and useful Improvements in Vises; and I do hereby declare the following to be a full, clear, and exact description of the invention, such as will enable others skilled in the art to which

it appertains to make and use the same.

This invention relates to vises; and it consists in the novel construction and combination of the parts hereinafter fully described and claimed.

15 In the drawings, Figure 1 is a longitudinal section through the vise. Fig. 2 is a front view of the same. Fig. 3 is a detail side view of the split ring for retaining the screw, and Fig. 4 is a front view of the same. Fig. 5 is

20 a cross-section on line $x-x$ in Fig. 1. Fig. 6 is a detail side view of the lower half-nut and nut-stock. Fig. 7 is a detail plan view of the plate under the cam-sleeve. Fig. 8 is a side view showing an upper half-nut added to the

25 lower half-nut and nut-stock. Fig. 9 is a longitudinal section through the same, and Fig. 10 is a cross-section on line $y-y$ in Fig. 8.

30 A is the stationary jaw of the vise, provided with the flange A' at its base and the central boss a projecting downwardly from said flange.

35 B is a stud screwed into boss a and provided with the nut b for securing the vise to the bench B'. A stationary circular plate C is interposed between the flange A' and the bench, and is provided with the hole c for the boss to pivot in, so that the vise can be swiveled around and secured in any desired position by tightening the nut b.

40 C' is a handle provided with a yoke at one end for turning the nut b, to which it is permanently pivoted by the pins c', which project inwardly from the ends of the yoke and engage with holes in the opposite sides of the nut. The handle can be folded on its pivots in either direction, so as to be in convenient position for operating the nut, as shown by the dotted lines in Fig. 1.

45 D is the sliding jaw of the vise, which is provided with the slide D', working back and forth in the stationary jaw.

E are the grips which are let into the jaws. Each jaw is provided with an incline d near the top and a steeper incline d' beneath it. Each grip has a flange E' at the top, which rests upon an incline d, and the grip slopes away from the bottom of its face and bears against the under side of the incline d', with its bottom resting on the shoulder e' on the jaw.

60 F are screws or rivets which secure the grips to the jaws. As each grip bears downwardly upon the jaw at the two places d and e' the strain is distributed and the jaws are little liable to work loose when the vise is used for heavy chipping. The steep inclines d' keep the grips down to their bearings and afford a means of adjustment, as the metal behind the grip-faces can be filed away until the grips fit tightly against the inclines d and shoulders e'.

65 F' is the vise-screw provided with the head f, having holes f' in its periphery. The vise-screw works in the channel g in the slide D' and is journaled in the flange G at the front of the sliding jaw.

70 H is a tubular handle for turning the vise-screw.

75 H' is a bolt which slides in the tubular handle H and engages with either of the holes f' in the vise-screw head. The bolt H' is provided with a spindle h, of smaller diameter than the bolt, and said spindle projects through the nut h', which is screwed into the end of the tube.

80 I is a spring, which surrounds the spindle h inside the tube and presses the sliding bolt into the holes in the screw-head.

85 I' is a button on the projecting end of the spindle, so that the bolt can easily be drawn back.

90 The handle H is provided with a socket i, which encircles the head of the vise-screw and permits the handle to be turned around to any convenient position before it is coupled to the screw-head by the sliding bolt. A nut i' upon the end of the vise-screw keeps the socket of the handle from slipping off the said screw-head.

95 J is a beveled collar on the vise-screw immediately behind the head f.

100 J' is a split retaining-ring provided with a

beveled recess for the collar J to turn in. The ring J' is cut into two parts, so that it may be slipped over the beveled collar, and the said ring is held in the recess j in the vise-jaw by 5 the plate K at the top, which is secured to the jaw by the screw k. The ring J' is divided by the beveled cut j', as shown in Fig. 3, so that the lower half of the ring is overlapped by the upper half and thereby held in the recess. 10 An oil-hole K' is drilled through the ring behind the plate K, so that the vise-screw bearing can be oiled after first removing the plate K. When the plate K is in place, it engages with the beveled portion k' on ring J' and 15 keeps the ring from turning, as well as prevents the oil-hole from becoming stopped up with dirt or filings.

L is the segmental nut, which engages with the under side of the vise-screw and bears 20 against the ends of the rectangular cavity L' in the stationary jaw.

In order that the vise may have what is known as a "quick action," the segmental nut is raised and lowered into and out of gear 25 with the vise-screw in the following manner: The nut proper L is provided with a dovetailed recess l in its under side. M is the nut-stock engaging with the said dovetailed recess and provided with the cheeks m, one of

30 which has a lug m'. The nut is made removable from the nut-stock, so that it may be made of softer metal than the nut-stock and be easily replaced when it becomes worn from contact with the thread of the vise-screw.

35 N is a double cam-sleeve, the ends of which abut against the ends of cavity L', and l' is a plate under the said cam-sleeve in the bottom of the cavity. N' is the operating-rod for the cam-sleeve, which is provided with a hole in

40 which the said rod may slide freely in a longitudinal direction. A flat n is formed on the rod N', and a projection n' in the hole of the cam-sleeve engages with this flat, so that the cam-sleeve may be turned by the rod, or

45 the cam-sleeve may be splined to the said rod, or otherwise connected to it, so as to accomplish the same result. The rod N' is journaled in the holes O in the flange A' of the stationary jaw, and its front end passes 50 through the hole O' in the flange G at the front of the sliding jaw. A trigger o is secured to the end of rod N' for turning it, and o' is a stop on flange G, which prevents the trigger from being turned too far around. P is a

55 spring, which is let into the recess p in flange G around the rod N'. One end of this spring is secured to the flange and the other end to the trigger, so that the torsion of the spring keeps the nut in engagement with the vise-screw, as shown in the drawings. When the trigger is turned so as to turn the double cam a quarter of a revolution, the side of the cam-sleeve strikes against the lug m' on one of the cheeks of the nut-stock and obliges the 60 nut to descend out of gear with the vise-screw if it has not previously descended by its own weight. When the operating-rod is turned

in the reverse direction by the spring or by hand, the double cam-sleeve presses against the plate l' under it and against the under side of the nut-stock above it, and the nut is raised into gear with the vise-screw without any bending strain being brought upon the operating-rod. In Figs. 8, 9, and 10 two segmental half-nuts are shown, one beneath the 75 vise-screw and the other above it. That part of the nut beneath the screw is raised and lowered by the cam-sleeve in a similar manner to the half-nut hereinbefore described. The upper part R of the nut is provided with 80 the dovetailed recess r, and its nut-stock S engages with said recess, so that the nut can be renewed when worn. The nut-stock S is provided with cheeks s, which extend downwardly at each end of the cheeks m of the 85 lower nut-stock and upon each side of the nut and are joined onto the plate l' under the double cam-sleeve. T are projections 90 consisting of screws or pegs which project through the sides of the cheeks s. The cam-sleeve strikes against the projecting ends of these screws and raises the upper half-nut at the same time as the opposite side of it strikes against the lug m' on the stock of the lower 95 half of the nut and depresses the said lower half-nut.

The nuts may be removably secured to the nut-stocks in many other ways besides by means of the dovetail-joints above described, and the dovetailed projection of the lower 100 nut-stock may be made of the same length as the cheeks, if desired, instead of being nearly as long as the nut, as this will make the parts easier to put together. The projections T may also be cast solid with the nut-stock, if desired, instead of being screws projecting through its side cheek. 105

This vise is specially adapted for jewelers' use and for fine work generally. It will hold either wood or metal equally well, and 110 may be made out of any material preferred.

What I claim is—

1. The combination, with the vise-screw provided with a beveled collar, of the circular retaining-ring formed of two separate 115 parts having overlapping beveled ends and secured in a circular recess in the sliding jaw and provided with a circular beveled recess for the said collar to revolve in, substantially as set forth.

2. The combination, with the vise-screw provided with a beveled collar, of the circular retaining-ring adapted to fit into a circular recess in the sliding jaw, and formed of two separate parts having overlapping beveled ends, and having a circular beveled recess for the said collar to turn in, the upper part being further provided with an oil-hole and a beveled portion at its outer edge, and a removable plate secured to the vise-jaw 125 and engaging with the beveled portion on the edge of the ring and covering the oil-hole, substantially as set forth.

3. In a vise, the combination, with the

vise-screw, of the segmental nut arranged beneath it and provided with a nut-stock having cheeks m and the lug m' , the revolute double cam-sleeve for raising the nut-
5 stock, the segmental nut arranged above the said vise-screw and provided with cheeks s , extending downwardly at each end of the said cheeks m upon each side of the screw and joined onto a plate under the cam for
10 receiving the reverse thrust of the said cam,

and the projections T on the said cheeks s for the cam to strike against, substantially as and for the purpose set forth.

In testimony whereof I affix my signature in presence of two witnesses.

EDWARD DAWSON.
